ATTORNEY.

UNITED STATES PATENT OFFICE.

CHARLES HORN, OF MILLBOURNE, PENNSYLVANIA.

SNAP-SWITCH.

1,133,285.

Specification of Letters Patent. Patented Mar. 30, 1915.

Application filed October 13, 1913. Serial No. 794,764.

To all whom it may concern:

Be it known that I, CHARLES HORN, a citizen of the United States, residing at Millbourne, Delaware county, Pennsylvania, have invented certain Improvements in Snap-Switches, of which the following is a specification.

My invention is a snap switch having a fulcrumed switch blade with a cam fixed thereto, in combination with a fulcrumed lever provided with a spring coöperating with the cam, whereby the switch blade is automatically thrown into and out of engagement with terminals when the lever is rocked 15 through a definite arc past the center of oscillation of the bar and cam.

The primary object of the invention is to provide a simple, compact and inexpensive construction that is positive and reliable in action and has a minimum tendency to arc- 20 ing.

The characteristic improvements will more fully appear from the following description and the accompanying drawings in illustration thereof.

In the drawings, Figure 1 is a sectional view taken through a wall receptacle containing my improved switch, the section being taken on the line 1—1 of Fig. 2; Fig. 2 30 is a sectional view taken on the line 2—2 of Fig. 1; Fig. 3 is a sectional view taken on the line 3—3 of Fig. 1; and Fig. 4 is a perspective view of detached details of construction.

As shown in the drawings, the wall 1 is 35 provided with a recess 2 containing the receptacle 3.

A bracket 4, preferably stamped out of sheet metal and comprising the bearings 4^a and 4^b, is secured within the receptacle 3, to 40 the base 3^a thereof, by screws 5 passing through such base 3^a and bearings 4^a.

A switch blade 6, which may be stamped out of sheet metal, is fixed to a bearing 7 having thereon an arbor 8 which is journaled in one of the members 4^b, the parts 6 and 7 being electrically separated by the insulation 9. A curved bearing or cam 10, containing the longitudinal slot 10^a, is supported by the bearing 7 and a bearing 7^a, 50 the latter being connected with a bearing 4^b by an arbor 8^a.

A sheet metal bar 11, which is fixed to the receptacle 3 by screws 12 (set in the lugs 3^b thereof) and to the wall by screws 13, is 55 provided with the bearings 11^a and contains a slot 11^b. A lever 14 passes through the

slot 11^b into the slot 10^a and is fulcrumed on the bearings 11^a by the pin 15.

A coiled spring 16 is disposed on the lever 14, between the shoulder 14^a thereof and a 60 curved bearing 17, containing a slot 17^a through which the lever passes, the bearing 17 riding on the inner surface of the cam or bearing 10 and moving on the lever.

Sheet brass plates 18 are fixed in the face 65 of the receptacle 3 by screws 19, and the respective plates have secured thereto the bent sheet metal phosphor bronze terminals 20 and 21, which are provided with the respective blades 20^a and 21^a for engaging the 70 respective ends of the bar 6, the terminals being yoke like in construction.

The plates 18 are connected, by binding screws 22, with the respective wires 23, the wires being held on the screws by lugs 18^a 75 formed on the plates and bent over the loops 23^a of the wires.

It will be understood that with the lever 14 in the position illustrated in Fig. 1, the blade 6 is out of contact with the blades 20^a 80 and 21^a. When, however, the lever 14 is pushed in the direction of the arrow, the bearing 17 will slide on the cam or bearing 10 and compress the spring 16 until the axis of oscillation of the cam has been passed, 85 when the spring will throw the cam 10 and blade 6 so that the ends of the latter will engage between the respective blades 20^a and 21^a and close the circuit.

Having described my invention, I claim:

1. A switch having a terminal, a fulcrumed switch blade, a bearing connected with said blade and extending across the fulcrum thereof, a lever having a bearing engaging said first named bearing, and a 95 coiled spring on said lever and acting against said second named bearing for throwing said blade, said lever being fulcrumed eccentrically to the fulcrum of said blade.

2. A switch having a terminal, a fulcrumed switch blade, a bearing connected with said blade and having a curved surface eccentric to the fulcrum thereof, a lever having a bearing engaging said surface, and 105 a spring acting against said bearing for throwing said switch blade.

3. A switch having a terminal, a fulcrumed switch blade, a cam connected with said blade, the bearing surface of said cam 110 approaching closest at its median point to the fulcrum of said blade, and a lever ful-

- crumed eccentrically to said blade and movable over said surface to rock said blade.
4. A switch having a terminal, a fulcrumed switch blade, a lever, a bearing connected with said blade and having members engaging an end of said lever between them, a device carried by said lever and movable thereby over said bearing, and a spring connected with said device for pressing it 10 against said bearing.
5. A switch having a terminal, a fulcrumed switch blade, a lever fulcrumed eccentrically to the fulcrum of said blade, a bearing connected with said blade eccentrically to the fulcrum thereof, a device movable along the length of said lever and along said bearing member, and a spring on 15 said lever and engaging said device for throwing said bearing and blade.
6. A switch comprising, in combination with a receptacle, bearing means fixed in said receptacle, a pair of terminals fixed in said receptacle, a switch blade fulcrumed on said bearing means, bearing means comprising a slotted member fixed to said blade, a bearing device fixed to said receptacle, a lever fulcrumed on said device and movable in the slot of said member, and a coiled spring on 20 said lever, said spring having a bearing movable on said member, whereby said member compresses said spring in the movement of said lever from the normal position to a point beyond the axis of oscillation of said blade and said spring then 25 throws said member and blade.
7. A switch having, in combination with a receptacle, a bracket having a bearing 30 fixed to the bottom of said receptacle and bearings extending transversely thereto, a switch blade fulcrumed on said bearings 40 second named, a curved member fixed to said blade eccentrically to its axis of oscillation, a bearing device fixed to said receptacle, a lever fulcrumed on said device so as to oscillate across the axis of said blade, 45 a coiled spring disposed on said lever between a bearing thereon and a movable bearing on said member, and terminals fixed in said receptacle, each terminal having blades for frictionally engaging respective ends of 50 said switch blade.
8. A switch having, in combination with a receptacle, a bracket having a bearing engaged to said receptacle, a switch blade fulcrumed on said bracket, a bearing fixed to 55 and insulated from said blade, a bearing device fixed to said receptacle, a lever fulcrumed on said device so as to be oscillatable across the axis of oscillation of said conductor, a spring on said lever movable across 60 said axis of oscillation whereby said second bearing is rocked, and terminals of different lengths fixed to said receptacle in positions to be engaged and disengaged by said blade in different positions thereof induced by 65 the movement of said member.

In testimony whereof, I have hereunto set my name this 11th day of October, 1913, in the presence of the subscribing witnesses.

CHARLES HORN.
